Primary Examiner — Katie Jane Stofko(74) *Attorney, Agent, or Firm* — Baker McKenzie LLP(57) **CLAIM**

The ornamental design for a magnetic privacy screen, as shown and described.

DESCRIPTION

FIG. 1 is a back elevation view of a magnetic privacy screen in accordance with my design;

FIG. 2 is a front elevation view thereof;

FIG. 3 is a right side elevation view thereof; and,

FIG. 4 is an enlarged perspective view of the upper left quadrant of the front and left side views thereof.

The broken lines shown in FIG. 4 indicate portions of the magnetic privacy screen that are shown enlarged and form no part of the claimed design.
